UNITED STATES PATENT OFFICE.

THOMAS O'BRIEN, OF COLDWATER, MICHIGAN, ASSIGNOR, BY DIRECT AND MESNE ASSIGNMENTS, OF ONE-HALF TO THE COLDWATER ROAD CART COMPANY, OF SAME PLACE.

VEHICLE-HUB.

SPECIFICATION forming part of Letters Patent No. 389,101, dated September 4, 1888.

Application filed April 4, 1888. Serial No. 269,579. (No model.)

To all whom it may concern:

Be it known that I, THOMAS O'BRIEN, a citizen of the United States, residing at Coldwater, in the county of Branch and State of Michigan, have invented certain new and useful Improvements in Hubs; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to vehicle-hubs of that class which comprises a wooden center and a metallic shell or case. In this class of hubs as heretofore constructed the center of the shell curves outward, leaving a space between it and the hub, which space is spanned at regular intervals by ribs or lugs cast with the shell and bearing against the hub. Such shells are difficult to adjust, and when contracting oftentimes crack, because of the resisting ribs or other projections bearing against the hub. Again, it is well known that moisture will find its way into the center of the hub by following the spokes, and will cause the center of the hub to expand. Obviously, if the shell tightly embraces this portion of the hub it must be rent asunder to accommodate the expansion of the hub, and when the space between the hub and shell is interrupted by ribs which divide the space into a series of compartments a free circulation of air cannot be had to take up and carry away this moisture, which must remain in the hub a longer time than necessary, causing decay.

The object of my invention is to obviate all or nearly all the objections existing against similar prior devices, and to provide a hub that will permit the shell to contract and expand and the hub to swell without detriment to the said shell, and which at the same time will have an uninterrupted space between the middle of the hub and the middle of the shell to permit of slight variations in size of either the hub or the shell, as previously intimated, and allow of a free ventilation, and which will rapidly dissipate any moisture that might find its way into the center of the hub. The shell

will have lugs at the ends of the spoke-openings to brace the spokes laterally. These lugs will project outward for a dual purpose—namely, to brace the spokes as far from the center of the hub as possible and to leave the interior of the shell perfectly smooth.

In the drawings, Figure 1 is a central longitudinal section of a hub embodying my invention; Fig. 2, a vertical cross-section on the line X X of Fig. 1.

The hub A is of usual construction, having the spoke-mortises *a* set staggering, and having the sides of its middle portion parallel. The shell B, incasing nearly the entire hub, save its inner end, is contracted at its ends and expanded or swelled intermediate of its ends, leaving an annular space, C, between the middle portion of the shell and the middle portion of the hub. The contracted ends of the shell fit the hub closely and are the only points that come in contact with the said hub. The spoke-openings *b* in the shell correspond in number and register with the openings *a* in the hub, and are provided at their ends with radial lugs *b'*, that extend outward and embrace the sides of the spokes. The sides of the hub being parallel and equal in diameter to the diameter of the inner end of the shell, manifestly the said shell can be readily slipped on or off the hub. When in position, the shell is held on the hub by the spokes D, which pass through the shell and enter the hub.

Having thus described my invention, what I claim, and desire to secure by Letters Patent, is—

The herein shown and described shell or case for vehicle-hubs, having its inner side smooth, and having its ends contracted to embrace the ends of the hub, and having its middle portion expanded to leave a space between it and the hub, and provided with spoke-openings and with radial lugs at the ends of the spoke-openings that extend outward, substantially as and for the purpose set forth.

In testimony whereof I affix my signature in presence of two witnesses.

THOMAS O'BRIEN.
